Specification for Design.

Patented Feb. 16, 1915.

Application filed October 24, 1914. Serial No. 868,531. Term of patent 14 years.

To all whom it may concern:

Be it known that I, ALBERT E. BATES, a citizen of Canada, residing at Nyack, in the county of Rockland and State of New York, have invented a new, original, and ornamental Design for Desk-Calendars, of which the following is a specification, reference being had to the accompanying drawing, forming a part thereof.

Figure 1 of this drawing is a plan view

of a desk calendar showing my new design; and Fig. 2 is a side elevation of the structure shown in Fig. 1.

I claim:

The ornamental design for a desk calendar, as shown.

ALBERT E. BATES.
